UNITED STATES PATENT OFFICE.

JAY BOYD, OF OMAHA, NEBRASKA.

SKIRT-VENT ADJUSTER.

No. 800,714.

Specification of Letters Patent.

Patented Oct. 3, 1905.

Application filed November 20, 1903. Serial No. 181,982.

To all whom it may concern:

Be it known that I, JAY BOYD, residing at Omaha, in the county of Douglas and State of Nebraska, have invented certain useful Improvements in Skirt-Vent Adjusters; and I do hereby declare that the following is a full, clear, and exact description of the invention, such as will enable others skilled in the art to which it appertains to make and use the same, reference being had to the accompanying drawings, which form a part of this specification.

This invention relates to a new and novel improvement in skirt-vent adjusters.

The object of my invention is to provide a skirt-vent adjuster by means of which the skirt may be held together at the vent in a neat and dressy manner in such a way that the skirt members will not separate.

In the accompanying drawings I have shown in Figure 1 a broken sectional view of the upper portion of a skirt, disclosing the vent as provided with my improvement. Fig. 2 shows a side view of the members comprising my skirt-vent. Fig. 3 shows a top view of one of the skirt-vent members, disclosing the manner of securing the shield-support, while Fig. 4 shows a front view of my skirt-vent adjuster.

In carrying out the aim of my invention I provide two counterpart members 6 and 7, each provided below with a perforated enlargement 8, through which extends a pivot-pin 9, these members being provided with the perforations α , through which suitable threads may be extended to be used in securing the vent-adjuster to the garment. One of the members above is provided with an ear 3, provided with a locking-slot 5, as shown in Fig. 4. The member opposite is provided with a supporting-pin c , which supporting-pin c performs a double function in that it secures the supporting-ear f , provided with perforations σ , as shown. This member f is bent to provide a shoulder, as shown in Fig. 3, so that the member 7 may be brought in alinement with the member 6. Now in securing these two members the pin c is held within the slot 5 in such a manner that there is provided a space between the two members 6 and 7, so that the folds of the fabric comprising the skirt will come adjacent one another and further permit a snug adjustment of the garment. In order to prevent these members

separating to disclose the nether garment, I provide the member 6 with the support f , to which is secured the cloth shield 4, as is disclosed in Fig. 1, so that there is a double thickness of material at the vent-opening.

The band 2, secured to the upper portion of the garment, is made to contain the member 3 and also the supporting member f , the pin c projecting through the upper band 2. This pin c in projecting is used as a means to secure the member 3 and performs a double function in that the belt usually worn with the skirt may be provided with an opening adapted to receive this pin c , so that this pin would hold the belt properly to the garment at the point where the members 6 and 7 are united. These members 6 and 7 are slightly bowed in the form of an ogee, as disclosed in Fig. 2, so as to more nearly conform to the human figure.

From the description it will be noticed that the two members 6 and 7 when closed are a suitable distance away from one another or apart to permit the fabric folding between the same, the two members coming in alinement. This is understood in referring to Fig. 2, where a side view of the members is shown, the members overlapping only at the bottom, where they are united. I further provide the member 6 with the projecting ear f , which supports the shield placed at the vent, while the pin used in securing the two members assists in holding the shield-support f and projects through the waistband 2 to be engaged by the belt used with the garment.

My skirt-vent adjuster may be incased in a fabric-holder to be sewed to the garments ready made or may be secured to the garment in the process of construction by means of stitching carried through the perforations α and σ .

The members 6 and 7 are preferably made of sheet spring-steel or other suitable material and are made of various sizes.

Having thus described my said invention, what I claim as new, and desire to secure by United States Letters Patent, is—

A skirt-vent adjuster, comprising two counterpart members, each provided below with a perforation, a pin within said perforation to pivotally unite said counterpart members, said members being provided with suitable thread-perforations, an ear provided with a locking-

slot secured to one of said counterpart members, said member opposite being provided with a pin adapted to extend through said locking-slot, and a projecting ear secured to 5 said last-mentioned member, adapted to form a support for a suitable shield, substantially as set forth.

In testimony whereof I affix my signature in presence of two witnesses.

JAY BOYD.
